UNITED STATES PATENT OFFICE.

ROY M. BENNETHUM, OF FREEPORT, ILLINOIS, ASSIGNOR TO STOVER MANUFACTURING & ENGINE CO., OF FREEPORT, ILLINOIS, A CORPORATION OF ILLINOIS.

WINDMILL.

Application filed January 21, 1927. Serial No. 162,541.

This invention relates to wind mills, and has for its object to provide, a mill of such class in a manner as hereinafter set forth, with means acting as a combined cross head 5 guide element and pump for supplying lubricant to the cross head, pitman connection for the latter and the cross head guides during the reciprocation of the pump rod or load shaft.

10 A further object of the invention resides in the construction of the cross head for receiving and distributing lubricant to the cross head guides and connection between the cross head and driving means therefor.

15 A further object of the invention is to provide, in a manner as hereinafter set forth, a wind mill, including a revoluble mill head provided with a pair of cross head guides and with one of said guides constructed and 20 arranged to provide a lubricant supply pump for the purpose of supplying lubricant to the cross head, guides therefor and pitman connection for the cross head during the reciprocation of the latter.

25 Further objects of the invention are to provide, in a manner as hereinafter set forth, in a wind mill, a combined operating and lubricant supply means for the pump rod or load shaft which is simple in its construction and arrangement, strong, durable, compact, thoroughly efficient in its use, readily assembled, and comparatively inexpensive to manufacture.

With the foregoing and other objects in view the invention consists of the novel construction, combination and arrangement of parts, as hereinafter more specifically described and illustrated in the accompanying drawings wherein is shown an embodiment 40 of the invention, but it is to be understood that changes, variations and modifications can be resorted to which fall within the scope of the claims hereunto appended.

In the drawings wherein like reference characters denote corresponding parts throughout the several views:

Figure 1 is an elevation of a wind mill in accordance with this invention.

Figure 2 is a section on line 2—2 Figure 1.

Figure 3 is a fragmentary view in vertical section, of the cross head and that guide rod therefor which provides the lubricant pump.

Referring to the drawings in detail 1 denotes a tower or derrick, provided with a platform 2. The head of the tower 1 indicated at 3 is formed with an opening 4 for the passage of the upright tubular wind wheel mounting or casing 5, in which operates the upright reciprocating pump rod or load shaft 6 of channel form. Fixedly secured to the top 3 by hold fast devices 7 is a base plate 8 having an upstanding central portion 9 formed with an opening 10 which aligns with the opening 4. The top edge of the upstanding portion 9 of the base plate 8 is grooved, as at 11 to provide a race for bearing balls 12. Supported upon the balls 12 is a cap member 13 having its lower end provided with an annular flange 14 which extends laterally therefrom, and has a depending outer portion 15 which is spaced from the casing 5. The lower face of the cap member 13 is formed with a groove 16 which opposes the groove 11 and receives the bearing balls 12. The flange 14 is ported, as at 17 for the purpose of supplying lubricant to the balls 12. The upstanding portion 9, in connection with the cap member 13 and bearing balls 12, constitutes a bearing for the revoluble mill head, which is referred to generally by the reference character 18.

As is well known, in the art of wind mills, the pump rod or load shaft is operated from a reciprocating cross head driven from a pair of spur gears operated by a pair of spur pinions mounted on the horizontal shaft 19 which carries the wind wheel 29. Only one spur pinion and spur gear is shown. The shaft for the spur gears is indicated at 21. A spur pinion is indicated at 22 and spur gear at 23. The shafts 19 and 21 are provided with bearings 24, 25 respectively. A wind vane is indicated at 26 and which is

carried by a pivoted, spring controlled supporting structure 27 connected to the mill head. The shaft 19 projects from one side of the mill head and has the wind wheel 20 connected upon the outer end thereof.

The mill head 18 comprises a lower or container section 28 and an upper or cover section 29. The section 28 is formed with a depending hub 30, which in connection with the member 13 provides what may be termed a turn table. The section 28 has arranged therein an upstanding tubular part 31 which forms a continuation of the hub 30 and formed integral therewith are upper and lower horizontally disposed tubular supports 32, 33 respectively. The support 32 has the bearings 25 arranged therein and the support 33 has the bearings 24 arranged therein. The supports 32 and 33 are arranged on opposite sides of the tubular support 31. Interposed between the tubular support 32 and support 31 is a lateral extension 34 arranged at the upper end of the support 31 and which is formed with a vertically disposed opening 25. Formed integral with the top of the support 33 and with one side of the support 31 is an upstanding socket forming member 36, and the socket provided thereby is indicated at 37. The member 36 is formed with a lateral opening 38 having the wall thereof threaded. The support 31 in connection with a part of the section 28 provides a lubricant well 39. The section 28 in proximity to hub 31 has a depressed part 40 forming a pocket 41. The tubular support 33 is extended laterally as at 33' for supporting the shaft 19. The support 33 and extension 33' forms an oil well, and supported from the tubular portion 33 is a pulley 33" over which travels a cable 33''' for pulling the mill out of the wind.

Secured in the socket 37 by the holdfast device 42, is an upstanding cross head guide 43, of appropriate height, and constructed preferably of a solid bar of cylindrical cross section. Opposing the cross head guide 43 and extending through the opening 35, as well as being secured therein and to the bottom of the pocket 41, is a combined cross head guide and lubricant supply pump formed of an outer tubular section 44 and an inner reciprocating tubular section 45 of less length than the section 44. The section 44 at its lower end is formed with a flanged plug 46 provided with a horizontally disposed port 47 and a vertical port 48. The port 47 opens at diametrically opposed points with respect to the section 44 in proximity to the bottom thereof. The port 48 opens into the interior of the section 44 and is normally closed by a check valve 49. The section 44 at the upper terminal portion thereof is provided with a pair of lengthwise extending diametrically opposed

slots 50 for the discharge of lubricant taken up from the well 39. The section 45 at its upper end is formed with a diametrically extending pin 51, which is fixedly secured to the section 45, below the top edge thereof and said pin 51 extends through the slots 50 and projects a substantial distance laterally with respect to each of said slots. Secured within the lower end of the section 45 is a short, tubular member 52 which establishes communication between the sections 44 and 45 and the upper end of said member 52 is normally closed by a check valve 53. The section 44 is fixedly secured in position and communicates with the pocket 41 whereby on the operation of the section 45, the lubricant will be drawn into the section 44 when the section 45 moves upwardly and when the latter moves downwardly the section 44, will be closed to the pocket 41, but the lubricant drawn into the section 44, will be forced up into the section 45 and be discharged through the slots 50 into the cross head whereby lubrication for the latter will be had and for other purposes to be presently referred to.

A reciprocating cross head is referred to generally by the reference character 54 and it comprises a body portion 55 having a cup-shaped top 56 and a pair of vertically disposed openings 57, 58 which open into the cup-shaped top 56. The body portion 55 is furthermore provided with a horizontally disposed opening 59, the bottom wall of which is formed with a vertically disposed opening 60 and the top wall with a depending transversely extending tubular portion 61. The cup-shaped top 56 of the body portion 55 forms a lubricant receiving recess 62, having the bottom 63 thereof inclining downwardly from the opening 58 towards the opening 57. The body portion 55 is furthermore formed with a depending port 64 of V-shape cross section and which opens into the tubular portion or part 61 for supplying lubricant thereto. Secured in the opening 57, as well as the opening 58, is a bearing sleeve 65 and one is employed for the cross head guide 43 and the other for the stationary section 44 of the combined guide and lubricant pump. Depending from the cross head 54 is a coupling member 66 for the pump rod or load shaft 6, and said member 66 is formed with a shank 67 which extends upwardly through the opening 60 and carries a securing means 68 therefor. The member 66 is fixedly secured to the pump rod 6, as at 69 and the said member 66 is formed with a web 70 which extends into the rod 6.

The guide 43 and section 44 of the other guide are connected together at their upper ends by a cross piece 71 which is fixedly secured in position. The section 29 of the mill head 18 is mounted at its lower end

upon the section 28 and extends over the cross piece or bar 71 and is secured therewith by the holdfast device 72. The section 29 provides a cover for the cross head guide, 5 as well as the cross head and the mechanism arranged within the section 28.

Arranged in the tubular part 61 is a bearing sleeve 73, through which extends a pivot pin 74. The pin 74 projects laterally from 10 the tubular part 61, that is from each end of the latter, and has connected to each end the upper end of a pitman. Only one pitman is shown and which is indicated at 75. The pitmans are arranged on the outer sides 15 of the spur gears 23, and only one of the spur gears is shown, and the lower end of the pitman 75 is pivotally connected to a spur gear 23, as at 76.

The pin 51 is engaged by the cross head 20 54 on the upward movement thereof, whereby the inner section 45 of the combined guide and lubricant pump is elevated. The section 45 provides what may be termed a hollow piston or rather hollow pump piston 25 and operates to draw the lubricant into the section 44 and further operates to conduct the lubricant to the slots 50, so that it will be discharged into the recess 62 and when 30 discharged in the latter it will not only lubricate the cross head and cross head guides, but also lubricate the connection between the pitmans and the cross head.

It is thought the many advantages of a wind mill, constructed in accordance with 35 this invention, can be readily understood, and although the preferred embodiment of the invention is as illustrated and described, yet it is to be understood that changes in the details of construction can be had which 40 will fall within the scope of the invention as claimed.

What I claim is:

1. In a wind mill a reciprocatory cross head for operating a pump rod, and a pair 45 of stationary guides for and extending through the cross head, one of said guides open at its upper portion and including means arranged therein and operated by the cross head for supplying lubricant through 50 said open upper portion onto the cross head.

2. In a wind mill a reciprocatory cross head for operating the pump rod, a pair of vertically disposed stationary guides for and 55 extending through said cross head, one of said guides including means arranged therein and operated from the cross head for supplying lubricant upon the top of the cross head.

60 3. In a wind mill a reciprocatory cross head for operating a pump, said cross head provided with a recess in the top thereof, a pair of cross head guides extending through and above the cross head, one of said guides 65 provided therein with means operated from

the cross head for supplying lubricant to said recess.

4. In a wind mill a reciprocatory cross head for operating the pump rod, and a pair of spaced vertically disposed guides having 70 said cross head reciprocate thereon, said cross head having its top provided with a recess, and one of said guides provided therein with means operated from the cross head for taking up lubricant and discharging it 75 into said recess from the upper terminal portion of such guide thereby providing for lubrication of the cross head.

5. In a wind mill a pair of spaced guides one adapted to communicate with a lubricant 80 supply, a cross head reciprocating on said guides and providing means for operating the pump rod of the wind mill, a connection between said cross head and a driving means therefor, and that guide adapted to communicate with a lubricant supply provided therein with means operated from the cross head for taking up lubricant and discharging the same upon the top of the cross head 85 in proximity to the upper end of such guide 90 thereby lubricating the guides, cross heads and driving connection.

6. In a wind mill a combined guide and pump comprising a stationary, tubular outer section having its lower end formed with a 95 valve controlled lubricant intake and its upper end with a lubricant outlet, and a reciprocatory inner tubular section adapted to be operated in one direction from the cross head and discharging at its upper end into said 100 outer section, said inner section having its lower end formed with a valve controlled intake.

7. In a wind mill a combined guide and pump comprising a stationary, tubular outer 105 section having its lower end formed with a valve controlled lubricant intake and its upper end with a lubricant outlet, a reciprocatory inner tubular section adapted to be operated in one direction from the cross head 110 and discharging at its upper end into said outer section, said inner section having its lower end formed with a valve controlled intake, said inner section carrying means extending through said lubricant outlet and 115 adapted to be engaged by the cross head to provide for the operation in one direction of said inner section.

8. In a wind mill, a reciprocatory cross head for operating a pump rod, a pair of 120 stationary guides for and extending through said cross head, one of said guides being tubular and having a valve controlled lubricant inlet, said tubular guide further having a slotted upper terminal portion, and means 125 arranged within the tubular guide and operated from the cross head for supplying a lubricant through said slotted terminal portion and to the top of the cross head.

9. In a wind mill, a reciprocatory cross 130

head having means for connecting it to a driving element therefor, a recess at its top and a port leading from the recess to said means, a pair of spaced stationary guides extending through said cross head adjacent the end walls of said recess, one of said guides being tubular and having a valve controlled lubricant inlet, said tubular guide further

having a slotted upper end terminal portion, and means arranged within the tubular guide and operated from the cross head for supplying lubricants through said slotted terminal portion into said recess. 10

In testimony whereof, I affix my signature hereto.

ROY M. BENNETHUM.
